WATER SERVICE APPARATUS

John T. McGarry, Cincinnati, Ohio; Mary Frances McGarry, executrix of said John T. McGarry, deceased, assignor to Railroad Products Company, Cincinnati, Ohio, a corporation of Ohio

Application February 10, 1944, Serial No. 521,827

16 Claims. (Cl. 137—13)

1

My invention relates to hydrants and the like, and more especially to such apparatus so exposed as to require precaution against freezing, and to require drainage of the residue of water in the riser after each taking of water.

One object of my invention is to avoid connection of the riser-drainage means with a sewer or other receptacle for the drainage from which the riser and other parts contacted by the used water may be contaminated. This object is attained by use of a reservoir receiving the drainage from the riser immediately after each taking of water for use, and by using force of water from the supply main, at the next taking, to return the drained water from the reservoir to the riser to pass out therefrom with water coming directly from the main, for use.

It is necessary to admit air to the reservoir as the drainage is drawn therefrom and to allow escape of air from the reservoir as water drains into it from the riser. Another object of my invention, ancillary to the first described object, is to exclude from the reservoir contamination carried in the atmosphere from which the air enters the reservoir.

In order to reduce the amount of water in the reservoir by at least the amount drained each time thereto, it is necessary, since it is water diverted from the main stream coming from the main that operates to take the drainage from the reservoir, to permit this main discharge to continue until the required reduction of amount of water in the reservoir is attained. A further object, therefore, is automatically to lock the main valve against closing until the flow from the main has been sufficient to effect the required reduction of amount of water in the reservoir.

Concerning the object of removing the drainage from the reservoir, the novel means therefor is disclosed in my co-pending application, Serial 452,315, filed July 25, 1942, which has become abandoned and in my application, Serial No. 448,095, filed June 23, 1942, and which became abandoned December 3, 1943. In that respect, therefore, this application is continuous with the first mentioned prior application which in turn is continuous in part with the second mentioned prior application. Concerning the exclusion of atmospheric contamination from the reservoir, and the locking of the main valve, as above described, the novel means therefor is disclosed in my first mentioned prior application. No improvements other than are disclosed in the mentioned prior applications are disclosed herein.

Other objects, not above mentioned, will ap-

pear in the course of the following description, illustrated by the accompanying drawings, in which—

Figure 1 is a side elevation of a complete apparatus embodying my invention, certain portions thereof being shown in vertical cross section;

Fig. 2 is a schematic illustration of the apparatus, showing relative positions of certain parts in one stage of use of the apparatus;

Fig. 3 is a like illustration showing changed relative positions of said parts in another stage of use of the apparatus;

Fig. 4 is a sectional plan view of the lower portion of the apparatus, the section being on line 4—4 of Fig. 5;

Fig. 5 is a sectional side elevation of said lower portion, the section being on the vertical plane of the line 5—5 of Fig. 4;

Fig. 6 is a vertical section of said lower portion and portions thereabove, on line 6—6 of Fig. 5;

Fig. 7 is a horizontal cross section on line 7—7 of Fig. 5; and

Fig. 8 is a vertical section on line 8—8 of Fig. 4.

In Figs. 1, 2 and 3, the upper part of the apparatus is that of a hydrant used in supplying potable water to railroad trains; and in this example, including Figs. 4 to 8, inclusive, the means for using the newly admitted water from the main to remove the drained water from the reservoir comprises a motor driven by part of the newly admitted water and a pump driven by the motor and pumping the drained water from the reservoir into the riser. The primary consideration is the lower structure; and other kinds of structures upstanding from the ground level, or near or at the ground level, may have the disclosed lower structure. The upper structure is described for clearness.

In Fig. 1 is shown the pedestal 1 having a chamber entered at its bottom by riser 2. The pedestal top is a housing screwed to the top wall of the chamber. A spout 4 leads from one side of the chamber and has its end 5 threaded to receive a hose or the like. The top of the chamber has a stuffing box up through which extends operating rod 7 from within riser 2. The handle 8 has members straddling housing 3, and in collars 9 in the respective housing walls a square shaft 10 fits, across the interior of housing 3, with ends projecting at both sides thereof. The members of handle 8 fit the square projections of shaft 10; and in the housing an eccentric cam 11 fits this square shaft 10. When handle 8 is

down at one end of housing 3, against a stop lug 12, the cam 11 is up away from operating rod 7; but when handle 8 is swung over and down against a stop lug 13 at the opposite end of housing 3, the cam 11 swings down and depresses and holds down the operating rod 7.

The lower parts of the apparatus could occupy a pit into which one may descend for servicing those parts, as is well known in the art. I prefer to avoid a pit, and provide an extension 14 of the base of pedestal 1, with an opening closed by a cap 15 screwed into its rim and having in its top a socket 16 to receive a turning tool, and having a bottom downwardly opening socket 17. A recess in the pedestal wall is closed by a door 18, which has a vent opening 19. A casing tube 20 has its top end fitting in an annular flange 21 on the bottom of pedestal base extension 14. A vent pipe 22 curves upward and extends up through the pedestal base to end near door vent opening 19. The tubular strut 23 in casing tube 20 fits its top in cap socket 17 and has a vent opening 24 in its side near the opening of the vent pipe 22 from the casing tube 20. This strut tube has a handle 25 extending at both of its sides, near its top.

The casing tube 26 surrounds riser 2 with its top fixed in the waist of pedestal 1. The valve casing 27 has a liner 28 in the upper end of which the bottom of casing tube 23 fits; the bore 29 of liner 28 being continuous with and of the same diameter as the interior of riser 2. The casing 27 has, up from its bottom 30 an annular shoulder 31 holding a gasket 32 on which liner 28 has an exterior annular rib 33 resting, which, with an exterior annular upper rib 34, affords a snug fit of the liner 28 in the casing 27. At one side the liner 28 has a part continuous from upper annular rib 34 down to lower annular rib 33; this part fitting snugly against the inner wall of casing 27, at the left side as herein shown, as best seen in Fig. 5. The liner 28 projects below the part of the casing 27 which it fits, into a valve chamber 35 formed in the casing bottom part, to form the annular main valve seat 36. The water supply main 37 enters one side of this valve chamber 35.

The main valve 38 comprises a shallow cup carrying within it the gasket 39 held therein by a screw 40 threaded through the cup bottom, with a locknut 41 below the cup and a head 42 against the top of gasket 39. A helical spring 43 between the cup and the bottom of chamber 35 holds the main valve yieldingly up to its seat 36.

As herein shown, the reservoir 44 comprises a part 45 integral with valve casing 27, with open outer end having flange 46 around it receiving the open end of a part 47 shaped like a can. The parts 46 and 47 are hermetically sealed together, as by soldering or welding, for instance; it being important to exclude all impurities from the soil in which the reservoir is embedded. The reservoir top has the annular flange 48 into which fits the bottom of the before described casing tube 20. A drain port 49 leads from within the liner bore 29 slantingly downward into reservoir part 45, up from the main valve 38. In prior apparatus with similar valve operation, a sleeve valve connected to the main valve operating rod, as the rod 7, closes the drain port when the rod is lowered to open the main valve, and opens this drain port when it is raised to close the main valve. Such a valve 50 is used herein, but it is cup shaped with a bottom 51 just above which is its side port 52 to register with drain port 49

when the valve 50 has been raised in the closing of main valve 38. This cup valve 50 has a depending stem 53 on its bottom 51, fixing it to the head 42 of the main valve clamp screw 40 before described.

Cup valve 50 has in it a cross part 54 near its top, with an upstanding hub into which the bottom of the operating rod 7 is screwed; thus forming unitary connection with the main valve 38, 10 for the rod 7. When cup valve port 52 registers with drain port 49, with cup valve 50 in raised position as shown in the drawings, the drainage flows past cross part 54 and through ports 52 and 49 into the reservoir. A packing 50' fits in a 15 groove around in the cup valve bottom 51 to resist the pressure of the water from main 37 when the main valve 38 is down and open.

Integral with casing 27 and reservoir part 45 is the barrel 55 with closed bottom 56 and open top 20 concentric with and in a depression below the lower end of casing tube 20. This barrel 55 has in it the motor and pump unit. From a port 57 in the wall of liner 28 leads a duct 58 by registry with port 57, curving around and into the back 25 of barrel 55 as the inlet for the motor; the port 57 being between the main valve 38 and the cup valve 50. Above this cup valve 50 the liner wall has a port 59 from which leads, by registry, the 30 conduit 60 curving around and upward to port 59 from within the front of barrel 55 as the outlet for the motor. This upper port 59 preferably is so shaped that the heightened wall of cup valve 50 will close it when valve 50 is in its upper position as before described, when the main valve 38 is closed. Where ports 57 and 59 register with the 35 liner ports, packings 61 and 61' preferably surround the ports in recesses in the exterior of the liner walls and bear against the interior of casing 27. Liner 28 may be drawn up out of casing 40 27 with riser 2, carrying with it main valve 38 and drain valve 50 on the operating rod 7, for servicing these parts above ground level.

The motor and the pump as shown herein for example are of the well known Root type; with 45 the motor above the pump and the respective shafts of their rotors vertically continuous. The inlet port 62 of the pump is through the back wall of the barrel 55, next to the reservoir bottom. The pump outlet conduit 63 is unitary with barrel 55 and the before described motor outlet conduit 50 60. The opening of conduit 63 from the pump into conduit 63 is an elongated narrow slot to 55 spread the pump discharge in intimate contact with the motor discharge, so that obstruction of either discharge by the other is minimized.

The connecting stem of the main valve 38 and the cup valve 50 has a lateral projection with a vertical groove 65 receiving guidingly the inner end of a screw 66 to prevent turning of the cup 60 valve 50 which would defeat registry of the drain ports 52 and 49. Outside the liner wall, in which the screws 66 is carried, a packing 66' under the screw head, in a countersink, prevents leakage from the liner bore 29 of high pressure water 65 from the main 57.

The motor and pump unit body 67 is of the form of a vertical tube with a transverse partition 68; and it has a removable bottom 69 with gasket 69' and held by screws 70; and has a removable 70 top 71 with gasket 71'. As best seen in Fig. 6, the air chamber 72 is an upright cylinder with a unitary bottom 73. The bottom of this cylinder connects hermetically with reservoir 44 down in a socket 72' below and concentric with the before 75 mentioned top annular flange 48 of the reservoir,

The top 71 of the body 67 has the socket 74 for which the air chamber bottom 73 forms the lid, with a gasket 73'. Screws 75 through bottom 73 and top 71 into body 67 unify the body 67 and the air chamber 72. The socket 74 of the body top 71 contains the timing gears 76 which are fixed to the rotor shafts 77 that have bearings 78 in chamber bottom 73 and in the barrel bottom 69, with packings 80, 81 and 82 in bottom 69, partition 68 and barrel top 71, respectively. Accurately fitting the motor chamber are the coacting epicycloidal rotors 83; and likewise fitting the pump chamber are like rotors 84. The rotors 83 and 84 are fixed on the respective shafts 71. The pump rotors 84 are of much greater diameter than the motor rotors 83; as here shown in ratio of about three to one. This is so that there will be a rapid expulsion of the drainage from the reservoir, avoiding the use of too much of the water directly from the main 37, which flows up through the riser 2 along with the pumped drainage water from the reservoir. This is permissible, as the water from main 37 has much higher pressure than must be overcome by the pumped drainage water from the reservoir up to spout 4 or any extension thereof, as a hose leading, for instance, up onto the top of a railroad car being supplied with the water. Also there is to be made allowance for slippage of water in both motor and pump, so that the actual ratio will be less than the theoretical one, but sufficient.

The body 67 has in its walls the motor inlet port 85, the motor outlet port 86, the pump inlet port 87 and the pump outlet port 88, registering, respectively, with the openings 58, 60, 62 and 63 in the walls of barrel 55. As the body 67 is to be raised out of barrel 55, packings 89 are provided in recesses around the outer ends of ports 85, 86, 87 and 88 against the interior surfaces of barrel 55, to fit tightly yet be slidable up and down on these surfaces.

The lid 90 is secured to the top of air chamber 72 by screws 91; and the strut tube 23 has its bottom end screwed into a central opening in this lid 90, so as to serve as a vent from pedestal vent pipe 22 to the air chamber, at all times. It is readily understandable that only such a vent would serve the reservoir as the water enters or leaves it; but it has been found that this direct venting permits ready entrance of impurities from the atmosphere into the reservoir, which a screen or the like for the vent will not certainly prevent. It is preferred to limit the venting to strut tube 23 rather than through the large casting tube 20 because the latter would more easily admit dust, soot and other substances which, collecting on the entire lid 90, would more easily drop into air chamber 72 through such lid opening.

It will be seen that tube 23 serves as a strut to hold the mechanism firmly down in the barrel 55, and as a handle for lifting the mechanism above the ground for servicing, as well as the vent as just described. The connection of the casting tube 20 with the reservoir top excludes all matter from the surrounding soil in which the structure is embedded.

The air chamber piston 92 comprises a body plate 93 with a central hub 93' into which is pinned, with a filler 93'', the bottom end of the tubular stem 94, which extends up centrally in strut tube 23 with radiating arms 95 near its top end guidingly contacting the interior walls of this tube 23. The piston cup packing 96 has its rim upstanding around its holding plate 97 held

by screws 98 to the piston body plate 93. Such cup packing 96 is preferred as being effective without excessive tightness against the chamber walls; but I am not limited to use of it.

5 A finger 99 is fixed to an edge part of piston body plate 93, depending to enter downward through an opening 100 in the air chamber bottom 73. This opening allows passage of air from air chamber 72 into the reservoir as piston 92 descends upon exit of water from the reservoir, and in the opposite direction as water enters the reservoir and the piston 92 ascends.

The counterweight 101 surrounds and is guided by strut tube 23 and is connected to one end of chain 102 running over a sheave 103 in a slot 104 in the tube wall; the other end of chain 102 being connected to the upper end of piston stem 94. The sheave 103 has a shaft 105 in ears 106 on tube 23 at opposite sides of its slot 104. Weight 101 is unsymmetrical with its heavier part where it connects with chain 102 to hang with its diameter substantially horizontal. The counterweighting of the piston structure, and a making of the parts as light as is feasible, respectively make up and down movements desirably of like resistance, and minimizes friction so as not to depart too much from the conditions with free flow of air to and from the reservoir. Only slight lubrication is needed, and opening 100 affords scant facility to run from the air chamber mechanism into reservoir 72 to mingle with the drainage.

The piston 92 descends under atmospheric pressure thereon against atmospheric pressure on the water rising in riser 2; the less distance in proportion to the greater area of piston 92 relative to the area of exposed water surface in riser 2 around rod 1, departing from theory only by the effect of friction and weighting the piston 92. This also is true when water is draining into the reservoir. The nature of the counterbalance may affect either operation one way or the other; and the progressive change of disposition of chain 102 also varies that nature. Thus, as seen in Fig. 6 most clearly, most of chain 102 hangs at the outer side, resisting descent of the piston; which is as it should be, because the water is in the reservoir and not in the riser where it could more effectively resist the piston descent. Conversely, with piston 92 lowered, most of chain 102 hangs inside tube 23 where it more effectively permits descent of piston 92; again as it should be, because then the water is higher in the riser and can more effectively resist the piston descent. These conditions are favorable at all stages in the manner just described.

To augment these effects weight may be added only to that part of chain 102 that passes from either side to the other of sheave 103. Thus, as shown, blocks of this chain 102, which is a sprocket chain, are enlarged to act more effectively as weights, as the blocks 107. In Figs. 2 and 6, all of these enlarged blocks are at the outer side to resist descent of the piston 92 or aid its ascent; and in Fig. 3 all of them are at the inner side to resist ascent and aid descent of the piston.

When the apparatus is used for such purposes as supplying potable water to railroad cars there is almost never a less taking of water than is required to operate the pump long enough to empty the reservoir. But, while the apparatus is not intended for such purpose, only a small amount of water may be desired, as only a cupful; in which case if the operator closed the main valve 75 38 as soon as that small amount had been ob-

tained, only part of the reservoir water would be removed. If this happened many times, though the reservoir has an excess of capacity, the cumulative residues would preclude full drainage of the riser, which of course always is left full, whatever small amount of water has been taken. This makes it desirable automatically, without dependence upon care of the operator to take enough water, to prevent such premature closure of main valve 38; compelling sufficient flow of water, though it may not be wanted, to empty the reservoir every time the apparatus is used.

For this purpose, as exemplified herein, the casing 27 and reservoir part 45 have a rear extension in which is a horizontal shaft 102 with a bearing 109 on the extension wall. Here an arm 110 is fixed on shaft 108, extending forward under air chamber bottom opening 100 to be engaged by piston finger 99 when it projects down through opening 100 as previously mentioned. The shaft 108 has a second bearing 111 on the extension wall at the rear of casing 27; and here it has fixed on it the upright arm 112 with a front nose beveled downwardly forward at its top and entering a slot 113 in the wall of casing 27. The liner 28 has through its wall, at this slot 113, the detent opening 114 containing a pin 115 of length equal to the thickness of the liner wall and having its outer end engaged by the nose of arm 112. The drain valve cup 50 has lengthwise through its cross part 54 the guideway 116 which meets detent opening 114 when the cup valve 50 descends with opening of main valve 38. The outer end portion of guideway 116 is reduced to leave an annular shoulder 117 facing forwardly, and bolt 118 is guided in the reduced portion with a head 119 engaging shoulder 117 under pressure of a spring 120 between head 119 and a plug 120' in the front end of guideway 116.

Thus, when the main valve is opened downwardly, the bolt 118 registers with and springs out into the detent opening 114, pushing pin 115 backward and swinging upright arm 112 backward and arm 110 upward under air chamber bottom opening 100. The bolt 118 thus can prevent return of the main valve 38 upward for its closure. The detent opening 114 and pin 115 are larger in diameter than the protruding bolt 118 and its guideway part, so that pin 115 cannot enter the bolt guideway. Also the protruding bolt part has considerable clearance in the detent opening 114 for easy movement out of this opening when the main valve 38 is held fully open by its operating cam 111 swung down as in Figs. 2 and 3. Having the pin 115 separate from the arm 112 permits removal of the liner 28 and associated parts upward as before explained. The nose of arm 112 is beveled at its top because, to be free to act on pin 115 it must have clearance in slot 113 as indicated. So having, it can enter casing 27 when liner 28 is removed, and so must be pushed aside by the liner 28 as it is inserted into casing 27. Most of this construction is best seen in Fig. 8.

When the descending piston finger 99 pushes the shaft arm 110 downward, the shaft upright arm 112 is swung forward, pushing pin 115 forward, which pushes bolt 118 out of detent opening 114 against pressure of spring 120, leaving main valve 38 free to rise and close, in the position shown in Figs. 5 and 8, if cam 111 is swung up as seen in Fig. 1; thus stopping the flow of water. As this action cannot occur until the piston 92 has reached its lowest position due to the full previous drainage having been withdrawn from the reservoir by action of the flowing water, the

main valve closure and stopping this removal action is automatically prevented until the removal has been completed.

In the usual withdrawal of much more water than is required to empty the reservoir, the pump will be operated by the water idly except for pumping air from the reservoir and thus creating a partial vacuum therein with an overbalance of outside atmosphere to press piston 92 downward, whereupon it holds the bolt 118 in its release position against the pressure of its spring 120, all the more tightly throughout the continued taking of water. The piston descent is stopped by its engagement with the chamber bottom 13; thus not straining the shaft and arm assembly on bolt 118. Of course finger 99 is sufficiently accurately of such length and the shaft and arms likewise so proportioned and arranged that bolt 118 is properly held in release position with the piston 92 thus stopped. Also, the piston 92 has its rise stopped by abutments 90' on the bottom of the air chamber lid 90.

In Fig. 2, the main valve 38 has just shortly before been opened and an initial portion of water R has passed from the reservoir into the riser 2; bolt 108 having protruded into opening 114. In Fig. 3, water discharged in excess of riser content, which may have been any desired amount, is indicated at E; it being understood that these schematic views do not show parts in their true proportions. In Fig. 2 the piston 92 is descending; the water being pumped from the reservoir. In Fig. 3 the piston 92 is entirely down and has pushed the bolt 108 out of the opening 114, so that the operator can close main valve 38 whenever he has obtained the desired amount of water E.

The closure of upper liner and casing port when the cup valve 50 is raised is to protect the water in the ducts 68 and 69 from outer air impurities until it has leaked through the motor and pump back into the reservoir, which leakage may be negligible if the motor and pump are amply proof against slippage of water. As arranged, the riser is not entirely emptied, and the drain port 49 slants down to the reservoir, leaving a moderate head of water the upper surface of which, in drain port 49, is the only water surface exposed to the atmosphere when the reservoir is filled. Air will bubble in through this slight head, eliminating whatever partial vacuum had been created in the reservoir by operation of the pump by discharge of water after the reservoir emptied at the previous use. It is desirable to have some change of air in the reservoir, as with always the same body of air retained, this air would foster reactions and germination of its content, accumulating chemicals or germs from the many succeeding volumes of water.

It is preferred to have the reservoir capable of holding considerable drainage in excess of riser capacity, below air chamber 12 as indicated in Fig. 2. This accommodates excess water, as from a hose. It also moderates the range of partial vacuum. Rise of water into the reservoir 12 is permissible, though of course causing greater partial vacuum in its withdrawal. A vent means acting directly to the reservoir collects impurities from the inflowing air which cannot readily enter past the packing 96 of piston 92. It will be noted that the riser is washed at each use of any slight impurity coming onto its walls from the atmosphere, so that there is never any cumulative deposit of impurities as in a direct reservoir vent over the

reservoir water as just noted. Moreover, a cap C, shown dotted in Fig. 1, may cover the outlet of spout 4, minimizing entrance of impurities to the riser and onto the slight exposure of reservoir water in the drain port 49 as before mentioned. It also keeps pollution off of the spout threads which would enter a hose as it is screwed onto the spout 4.

Could the piston 92 not remove the bolt 108 to release position the discharge would continue until the next use of the apparatus. The chain weight blocks 107 may be made heavy in proportion to the efficiency of the motor and pump, so to resist descent of piston 92 that vacuum is created in the first stage of piston descent, and as weights 107 pass over and downward they add force of gravity in degree that they overcome counterweight 101, against the reduced air pressure in the reservoir, giving the piston 92 the more force to remove bolt 108 to allow main valve 38 to close. Also any vacuum in the reservoir promotes quick drainage from riser 2, lessening the chance of the water freezing on the riser walls and the rod 7; which freezing, cumulative, can build ice on these parts to the extent of clogging the riser and making the apparatus inoperative.

The piston 92 prevents vapor from the reservoir rising and condensing in the interiors of the upper parts of the vent means, as tubes 22 and 23, there to freeze or to adhere dust as is the case with a direct vent to the reservoir.

A usual habit of persons drinking is to withdraw and throw away a first portion of water, if a cup is used, or to allow considerable water to flow from a fountain before drinking. Also, nearly always more water flows to the drinking fountain basin than the user drinks; and children tampering usually will allow too much instead of too little water to flow for emptying the reservoir. Along with all the other advantages described for the apparatus, which as shown herein is of the type for railroad car watering, the bolt 108, avoiding speculation as to the just mentioned circumstances with a drinking fountain, is especially valuable in such a fountain. Therefore, this modified use, with upper parts designed as in drinking fountains, or other uses occurring in practice, as well as modifications of structure, I regard as within the scope of my invention as defined in the following claims.

I claim:

1. In water service apparatus, casing means, a main valve in said casing means, a main in water-delivering relation to said casing means, a riser in water-receiving relation to said casing means, said main valve being operative to permit or prevent flow from the main to the riser, a reservoir in water-receiving relation to said riser, a second valve operative to permit or prevent flow from the riser into the reservoir alternative with the flow from the main to the riser and invariably operative to prevent flow from the main directly to the reservoir, a motor, means admitting water from the space between the two valves into said motor when said main valve is open, a pump driven by said motor, having an inlet from said reservoir, means for admitting water from said motor to said riser beyond said second valve from said main valve, and means for admitting water from the pump into the riser along with the water admitted from the motor.

2. Water service apparatus comprising a riser and a reservoir into which drainage passes from the riser for storage after each use of the ap-

paratus, and means for exerting the force of water newly admitted to the apparatus upon said drainage, to dispose said drainage out of the reservoir, said apparatus comprising means whereby the disposed drainage is conducted into the riser under said force, and means holding air in common with said reservoir, having an operation to increase its air capacity as the drainage passes into the reservoir, and having an operation to decrease its air capacity as the drainage is disposed out of the reservoir.

3. Water service apparatus as set forth in claim 2, in which is included a device assistant to the increase of air capacity of the air-holding means in progressively increasing degree as the drainage passes into the reservoir and assistant to the decrease of air capacity of said air-holding means in progressively increasing degree as the drainage is disposed out of the reservoir.

4. Water service apparatus as set forth in claim 2, including flow-control means having operations, respectively, for permitting admission of forcing water and stopping said admission, and a control device operative to assume preventive relation to said flow-control means whereby it can prevent the admission-stopping operation of said flow-control means, upon admission-permitting operation of said flow-control means, said device having a subsequent operation in conjunction with a terminal stage of air-capacity-decreasing operation of the air-holding means, to restore said control device out of said preventive relation to permit admission-stopping operation of said flow-control means.

5. Water service apparatus as set forth in claim 2, including flow-control means having operations, respectively, for permitting admission of forcing water and stopping said admission, and a control device operative to assume a preventive relation to said flow-control means whereby it can prevent the admission-stopping operation of said flow-control means, said device having a subsequent operation in conjunction with a terminal stage of the air-capacity-decreasing operation of the air-holding means, to restore said control device out of said preventive relation to permit admission-stopping operation of said flow-control means, said apparatus also including a device assistant to the increase of air capacity of the air-holding means in progressively increasing degree as the drainage passes into the reservoir and assistant to the decrease of air capacity of said air-holding means in progressively increasing degree as the drainage is disposed out of the reservoir.

6. Water service apparatus as set forth in claim 2, in which is included means stopping the decrease of air capacity of the air-holding means in the course of continued operation of the force-exerting means after the drainage is disposed out of the reservoir, which force-exerting means, due to the stoppage of decrease of air capacity, can then reduce the pressure of air in the reservoir, whereby succeeding drainage into the reservoir is facilitated by the reduced pressure of the air therein relative to the pressure of air in the riser.

7. Water service apparatus as set forth in claim 2, in which is included means for stopping the decrease of air capacity of the air-holding means in the course of continued operation of the force-exerting means after the drainage is disposed out of the reservoir, which force-exerting means, due to stoppage of decrease of air capacity, can then reduce the pressure of air in the reservoir,

whereby succeeding drainage into the reservoir is facilitated by the reduced pressure of the air therein relative to the pressure of air in the riser, the reservoir and the riser being so proportioned and arranged in their drainage-exchanging relation that the drainage, in the terminal stages of its accumulation in the reservoir, presents a portion of drainage through which air passes from the riser into the reservoir without exposure of the top surface of the water in the reservoir to exterior atmosphere.

8. Water service apparatus comprising a riser and a reservoir into which the drainage passes from the riser for storage after each use of the apparatus, and means for exerting the force of water newly admitted to the apparatus upon said drainage, to dispose said drainage out of the reservoir, said apparatus comprising means whereby the disposed drainage is conducted into the riser under said force, an air chamber in air-containing continuity with said reservoir, and a piston movable in said chamber in response to venting movement of air in the reservoir and chamber incident to the passage of said drainage into and out of the reservoir.

9. Water service apparatus as set forth in claim 8, in which the piston ascends as the drainage passes into the reservoir and descends as the drainage passes from the reservoir, said apparatus including counteracting means having an operation to substantially neutralize the weight of said piston relative to the pressures incident to the passages of the drainage.

10. Water service apparatus as set forth in claim 8, in which the piston ascends as the drainage passes into the reservoir and descends as the drainage passes from the reservoir, said apparatus including counteracting means comprising a weight, a sheave member, and a flexible member passing over said sheave member and connected to said weight and to said piston to substantially neutralize the weight of said piston relative to the pressures incident to the passages of the drainage.

11. Water service apparatus as set forth in claim 8, in which the piston ascends as the drainage passes into the reservoir and descends as the drainage passes from the reservoir, said apparatus including counteracting means having an operation to substantially neutralize the weight of the piston relative to the pressures incident to the passages of the drainage, and means moved incident to the operation of said counteracting means, first to operate so as to resist descent of said piston and then to operate so as to assist said descent, in successive stages of the descent, and then first to operate so as to resist ascent of said piston and then to operate so as to assist said ascent, in successive stages of said ascent.

12. Water service apparatus comprising a riser and a reservoir into which drainage passes from the riser for storage after each use of the apparatus, and means for exerting the force of water newly admitted to the apparatus upon said drainage, to dispose said drainage out of the reservoir, said apparatus comprising means whereby the disposed drainage is conducted into the riser under said force, said force-exerting means comprising a motor driven by said newly admitted water, and a pump driven by said motor to effect the disposal of the drainage out of the reservoir, and said apparatus also including air-holding means holding air in common with said reservoir, capable of operation to increase its air capacity as the drainage passes into the reservoir, and

capable of operation to decrease its air capacity as the drainage is disposed out of the reservoir, said pump, motor and air-holding means being assembled as a unit for removal from and replacement into operative relation to said riser and said reservoir.

13. Water service apparatus comprising a riser and a reservoir into which drainage passes from the riser for storage after each use of the apparatus, and means for exerting the force of water newly admitted to the apparatus upon said drainage, to dispose said drainage out of the reservoir, said apparatus comprising means whereby the disposed drainage is conducted into the riser under said force, and also comprising flow-control means having operations, respectively, for permitting admission of the forcing water and stopping said admission, and a control device operative upon admission-permitting operation of said flow-control means to assume a preventive relation to said flow-control means whereby it prevents admission-stopping operation of said flow-control means, said device having a subsequent operation in response to a terminal stage of reduction of volume of drainage in the reservoir to restore said control device out of said preventive relation to permit the admission-stopping operation of said flow-control means.

14. Water service apparatus comprising a riser and a reservoir into which drainage passes from the riser for storage after each use of the apparatus, and means for exerting the force of water newly admitted to the apparatus upon said drainage, to dispose said drainage out of the reservoir, said apparatus comprising means whereby the disposed drainage is conducted into the riser under said force, a flow-control structure having movements, respectively, to permit or stop admission of the forcing water to the force-exerting means, a bolt movable on said flow-control structure, a member fixed relative to said flow-control structure, having detent means, a spring forcing said bolt into detaining relation to said detent means when said structure is moved to permit said admission, and control structure so related to the drainage in the reservoir and to said bolt as to move said bolt out of its detaining relation in response to a terminal stage of reduction of volume of said drainage in the reservoir.

15. Water service apparatus as set forth in claim 14, in which the control structure related to the drainage as therein set forth comprises a piston which is movable in response to movements of air due to changes of volume of the drainage in the reservoir.

16. Water service apparatus as set forth in claim 14, in which is included a casing and a liner withdrawable and insertible out of and into the casing, as a part of the riser and along with the flow-control structure, said liner being the therein mentioned member fixed relative to the flow-control structure and having an opening through its wall as the therein mentioned detent means, a first element movable on the casing and a second element movable in said opening, as parts of the therein mentioned control structure related to the drainage, said casing having an opening in its wall admitting said first element to engage said second element, said second element being movable by said first element for engaging the bolt to move it out of its detaining relation, and said second element being wholly contained within said wall of said liner when it has moved said bolt out of said relation, whereby said second element is out of retentive engagement with said casing

13

and permits the withdrawal and insertion of said liner.

JOHN T. McGARRY.
